UNITED STATES PATENT OFFICE.

CHARLES W. NYE, OF MINNEAPOLIS, MINNESOTA, ASSIGNOR TO THE MINNESOTA STOVE COMPANY, A CORPORATION OF MINNESOTA.

RESERVOIR FOR RANGES.

1,300,456.

Specification of Letters Patent.

Patented Apr. 15, 1919.

Application filed April 19, 1918. Serial No. 229,515.

To all whom it may concern:

Be it known that I, CHARLES W. NYE, a citizen of the United States, residing at Minneapolis, in the county of Hennepin and State of Minnesota, have invented certain new and useful Improvements in Reservoirs for Ranges, of which the following is a specification.

My invention relates to reservoirs for ranges and has for its object to provide means for attaching a reservoir to a range in such manner that the water in the reservoir may be quickly heated by the heat communicated from the range. Another object is to provide an attachment of this kind which does not necessitate any material change in the customary sheet metal wall of the range and which is economical in its manufacture. Another object is the provision of means whereby the reservoir may be easily and quickly attached to the range or detached therefrom as desired. Another object is the provision of a construction whereby the attractive appearance of the range is not lessened when it is desired to use the range with the reservoir removed.

I accomplish the objects of my invention by securing the reservoir to the range so that one of the sheet metal walls of the reservoir will be directly in contact with one of the customary sheet metal walls of the outside body of the range and provide means for maintaining an intimate contact between these two walls so that there may be no air spaces or pockets between them.

The result of this construction is that the heat from the combustion flues is readily transmitted through the two comparatively thin sheet metal walls to quickly heat the water in the reservoir. In order to secure this intimate contact of the two walls, I provide means to apply outward pressure upon the reservoir contacting portion of the wall of the range at or near its central point.

In this way an outwardly bulged portion of the wall of the range body is provided and the reservoir is secured in place upon the range in such manner that the continuous wall of the reservoir is placed under tension and forced into intimate contact

with said bulged portion of the range body. The occurrence of air pockets between the walls is thus prevented. A slight bulging of the sheet metal wall of the body is sufficient to accomplish this result and the appearance of the range is not in any way impaired when the reservoir is removed.

The full objects and advantages of my invention will appear in connection with the detailed description thereof and are particularly pointed out in the claims.

In the accompanying drawings, which illustrate my invention,

Figure 1 is a view in perspective of a portion of a range having a reservoir attached thereto. Fig. 2 is a side view of the reservoir as it appears when not attached to the range. Fig. 3 is a view in vertical section on the line 3—3 of Fig. 1. Fig. 4 is an enlarged sectional view showing the manner of securing the bottom of the reservoir to the range. Fig. 5 is a face view of the bar which I use showing how it is attached to the range. Fig. 6 is a view of a modified form of bar. Referring to the drawings in which the same part throughout the several views is designated by the same numeral,—

10 designates the body of a range having the end wall 12 of the customary sheet metal of which the walls of the range are constructed. 13 designates a reservoir for heating water, and this reservoir is made of sheet metal and has a bottom designated by the character 14 and a wall 16 designed to contact with the wall 12 of the body of the range. In order that this reservoir may be attached to the range or detached therefrom as desired, the following construction is provided. The top flange of the range is formed with two openings 18 within which are adapted to be hooked two curved lugs 20 extending from the top of the reservoir. To accommodate these lugs the wall 16 is turned inwardly at 22 and upwardly at 24 to form a recess 26. The top member 28 of the reservoir designated by the character 28 is secured to a flange on the portion 24 and the lugs 20 extend from the top member down into the recess 26 in such manner that they may be readily hooked into the

- holes 18 to support the reservoir. It is obvious that this construction provides a hinged connection for the reservoir and that when the hooks have been placed in the holes 5 and the reservoir allowed to swing downwardly, it will be securely locked at the top in place on the range. The wall 16 of the reservoir will thus swing into contact with the wall 12 of the body of the range.
- 10 The means for bringing about an intimate contact of these two walls will now be described. A member having a horizontal bar portion 30 and a vertical bar portion 32 is secured to the inside of the body wall. The bar 32 extends upwardly from the middle of the bar 30 and the two are preferably cast integrally. The bar 32 is slightly curved, as best shown in Fig. 3, and it may be strengthened by an integral rib 34. The bar 30, which has a flat portion for contacting with the body wall is secured thereto at about the bottom line of the reservoir by bolts 36 passing through its ends and through the body wall. It is obvious, therefore, 25 that the entire periphery of the reservoir contacting surface of the body wall is held in place in a common plane, and if outward pressure be applied at or near the center of this surface it will be bulged outwardly or curved in all directions with the curvature beginning and extending from the periphery of the reservoir contacting portion of the body wall. In order to produce this bulging, in the form of invention 30 shown in Fig. 3, the bar 32 is curved and the upper end of this bar is secured to the body wall by a bolt 38. It is evident that the center of this bar is somewhat out of alignment with the ends and will exert pressure upon the body wall of the range to 35 bulge the same outwardly. The reservoir has a notched lug 40 secured to its bottom, and when it is desired to attach the reservoir the curved lugs 20 are inserted in the holes 18 and the reservoir allowed to swing downwardly so that its wall 16 comes into contact with the body wall 12. A screw-threaded bolt 42 is inserted in the notch of the lug 40 with the screw threads 44 engaging a hole 46 in the bar 30, this hole in connection with the adjacent hole in the body wall constituting a hole which extends entirely into the wall of the range. The hole in the bar may have its surrounding wall thinned in order to more readily cooperate with the screw threads 44. A few turns of the bolt 42 will tension the wall of the reservoir into intimate contact with the body wall of the range.
- 40 In the form of invention shown in Fig. 6 instead of making the bar 32 with a curved surface, it is straight, and therefore in this figure I designate the bar by the character 32' in order to distinguish from the curved bar 32. In order to obtain a bulging effect

with this form of bar, I provide the central portion thereof with a lug 48. It is evident that this lug will exert pressure upon the body wall and produce the same bulging effect thereon, as is produced by the curved 70 bar 32.

The operation and advantages of my invention will be apparent from the foregoing description. When the reservoir is attached to the range the two engaged walls thereof 75 are maintained in intimate contact, and this is accomplished without making any radical changes in either the reservoir or the range. Such additional construction as necessary is simply and cheaply manufactured and easy 80 to apply. In case it is not desired to use the reservoir, this may be left off and the range does not have its ornamental appearance diminished. Under this condition an ornamental disk may be used for closing the 85 hole in the wall of the body leading to the hole 46 in the bar 30.

I claim:

1. A reservoir attachment for ranges comprising a bar adapted to be secured to the 90 inside of a wall of the range, and means associated with said bar whereby the reservoir contacting portion of said wall will be bulged outwardly.

2. A reservoir attachment for ranges comprising means for attaching a reservoir to a range with a wall of the reservoir in contact with a wall of the range, and means engaging a restricted area of the reservoir contacting portion of the wall of the range 100 to cause outward bulging of the same.

3. A reservoir attachment for ranges comprising means adapted to be secured to the inside of a wall of the range for bulging a portion thereof outwardly, and means for 105 securing a reservoir to the range with one of its walls in contact with said bulged portion.

4. A reservoir attachment for ranges comprising means for forcing one of the walls 110 of the range outwardly into a shallow cup-like form, and means for securing a reservoir to the range with one of its walls tensioned over said cup-like wall.

5. A reservoir attachment for ranges comprising a member adapted to be secured to the inside of a wall of the range, said member having a horizontal bar portion and a vertical bar portion extending upwardly from said horizontal portion, the latter portion being secured to the wall of the range 120 at about the bottom line of the reservoir and the vertical portion being secured to the wall of the range near the top thereof, and means on said vertical portion to cause outward bulging of the reservoir contacting portion of the wall of the range.

6. A reservoir attachment for ranges comprising a reservoir having curved lugs extending outwardly from the top thereof for 130

engagement with holes in the top flange of the range, means for forcing the reservoir contacting portion of the range wall into outwardly bulging position, a notched lug 5 secured to the bottom of the reservoir, and a screw-threaded bolt extending through the notch in said lug with the screw threads en-

gaging a hole in the wall of the range, whereby the contacting wall of the reservoir is tensioned over said bulged range wall. 10

In testimony whereof I hereunto affix my signature.

CHARLES W. NYE.
